(57) **CLAIM**

The ornamental design for a towel bar, as shown and described.

DESCRIPTION

FIG. 1 is a perspective view of a towel bar showing our new design;

FIG. 2 is a front view of the towel bar;

FIG. 3 is a rear view of the towel bar;

FIG. 4 is a left side view of the towel bar;

FIG. 5 is a right side view of the towel bar;

FIG. 6 is a top view of the towel bar;

FIG. 7 is a bottom view of the towel bar; and

FIG. 8 is a cross-sectional view of the towel bar; and,

FIG. 9 is a perspective view of a second embodiment of the towel bar, which is the same as the first embodiment except for the shape of the wire.

The broken lines in the drawing illustrate environmental matter and form no part of the claimed design.
